WILLIAM D. ANTRIM, OF GLOUCESTER CITY, NEW JERSEY, ASSIGNOR TO WELSBEACH COMPANY, OF GLOUCESTER CITY, NEW JERSEY, A CORPORATION OF NEW JERSEY.

GAS HEATER.

Application filed August 19, 1924. Serial No. 732,918.

The present invention relates to gas heaters of the type known as radiant heaters, and has for its object to improve the construction and efficiency of heaters of this type.

A preferred embodiment of the invention is illustrated in the accompanying drawings, in which:

Figure 1 is a front elevation of a heater constructed in accordance with my invention;

Figure 2 is a horizontal section, on a larger scale, on the line II—II of Figure 3, the lateral extension members and extension legs being removed;

Figure 3 is a transverse vertical section on the line III—III of Figure 2;

Figure 4 is a detail plan view of the burner;

Figure 5 is a view partly in elevation and partly in section, on a larger scale, of a portion of the burner manifold;

Figure 6 is a section on the line VI—VI of Figure 5;

Figure 7 is a detail plan view of an element of a burner tip;

Figures 8 and 9 are, respectively, a rear elevation and an end view of the fireclay header;

Figure 10 is an inverted plan view of the header;

Figure 11 is a section on the line XI—XI of Figure 10, and

Figure 12 is a detail view of the metal cover for the upper edge of the header.

In the illustrated embodiment of the invention, the heater comprises a sheet metal back 2 having integral forwardly extending sides 3. These sides have outwardly flared front extensions 4, the front edges of which fasten to the outer rearwardly extending flanges 5 of corner uprights 6. A pair of supporting legs 7 is fastened to the back 2 and an additional pair of supporting legs 8 is secured to the lower ends of the corner uprights. A front bar 9 has its ends secured to the lower portions of the corner uprights by screws 10. This bar is bowed outwardly, as shown in Figures 1 and 2. Another bar 11 is provided at the top of the heater and is fastened to the upper edge of the sheet metal back 2, the ends of the bar being fastened to the sides 3. The bar 11 has a member 12 detachably mounted thereon, said member having a suitable con-

figuration to give a finished appearance to the top of the heater. Members 13 extend over the upper edges of the sides 3 and are fastened at one end to the ends of the bar 11 by screws 14, and are fastened at the other end to the upper ends of the corner uprights by knobs 15 which screw onto threaded stems (not shown) extending upwardly from the corner uprights and passing through openings in the members 13.

The corner uprights, the front bar 9, the members 12 and 13 and the knobs 15 are formed of cast or wrought metal and are preferably provided with an ornamental de-

sign to give a pleasing appearance to the heater. In order to further enhance the appearance of the heater, ornamental exten-

sions 16 may be secured to the lower portions of the corner uprights. These extensions are curved and extend laterally and forwardly from the corner uprights and have ornamental legs 17 detachably secured to their outer ends. Additional triangular shaped ornamental wings 18 are mounted on the extensions 16 and are detachably secured to the corner uprights and to the extensions.

Located between the sheet metal sides 3 and fastened at its ends thereto is a sheet metal deck 19 having an upward extension 20 at its rear edge. This deck has a longitudinal slot 21 therein through which the burner tips project, as will be hereinafter explained. The deck also has a depressed ledge 22 at the front thereof upon which the rear edge of a sheet metal hearth 23 rests.

The forward edge of the hearth is supported upon a shoulder 24 of the front bar 9. Sheet metal side pieces 25 extend upwardly from the ends of the hearth. The for-

ward edges of these side pieces engage between the inner rearwardly extending flanges 26 of the corner uprights and lugs 25^a. The rear edges thereof engage be-

tween the sides 3 and fireclay end pieces to be described later. The hearth and the side pieces have a vitreous enamel coating pro-

vided with markings 23^a giving the effect of tile, and greatly adding to the attractiveness of the heater. The hearth can be easily

dismounted as desired, by first removing the front bar. Fastened, by screws 27, to the portion of the deck 19 adjacent the ledge 22 is a metal finishing and clamping strip

28, preferably of brass. This strip has a

downwardly and rearwardly curved forward edge portion 29 between which and the ledge 22 the rear edge of the hearth engages, whereby assembly and disassembly is facilitated.

Extending beneath the slot 21 in the deck and suitably fastened at its ends to the sides 3 is a burner manifold 30. This manifold has a series of screw threaded openings 31 10 in its upper side into which are screwed the brass bushings 32 having burner tips 33 of refractory material permanently mounted therein. As shown, each burner tip has four holes, but the number and size of the 15 holes may be increased or decreased as conditions of gas supply and pressure may require. Seated within each bushing, upon a shoulder 34, is a distributing element 35, as shown in detail in Figure 7, preferably 20 formed of the same material as the burner tip and functioning to distribute the gas uniformly to the several openings of the tip and to prevent flash back. The tip has integral projections 36 at its lower end, 25 whereby, when the tip and distributing member are assembled within the bushing, the lower end of the tip will be properly spaced from the upper end of the distributing member. Interposed between a shoulder 30 34^a of each bushing and the upper face of the manifold is a gasket 37 whereby gas-tight connections are provided between the bushings and the threaded openings in the upper side of the manifold. Interposed between the openings 31 are lugs 38 which are integral with the manifold and extend upwardly slightly above the upper ends of the burner tips, for a purpose which will be explained later.

Connected to the central portion of the burner manifold is a Bunsen tube 39. This tube, having a suitable gas connection 40 at its forward end, extends beneath the hearth and the manifold and, at its rear end, curves 45 upwardly and forwardly for attachment to the rear side of the manifold. The gas connection is provided with a valve 41, the stem 42 of which extends through an opening in a guard 43 detachably secured to the lower edge of the front bar 9. The stem has a suitable operating handle 44 mounted upon its outer end. The Bunsen tube has a series of air admission openings 45 50 therein adjacent its forward end adapted to be controlled by a sleeve 46 slidably mounted on the forward end of the tube. This sleeve has a forwardly extending rod 47 fastened thereto and provided with a laterally extending end portion 48 engaged by 55 an eye 49 on the end of a stem 50 which projects through the guard 43. A coil spring 51 surrounds the stem between the eye 49 and the guard and the stem has a button 52 on its forward end. It will be 60 apparent that the spring normally maintains

the sleeve in the position shown in Figure 3, whereby the openings 45 are fully uncovered. By pulling outwardly on the knob 52 the openings 45 can be more or less restricted, whereby the sleeve 46 acts as a choke to give a rich mixture when lighting the heater.

Integral with an intermediate portion of the Bunsen tube is an annular flange 53 against which is seated an annular disk 54. 75 Another disk 55 is secured between the front end of the tube and a flange 56 on the gas connection 40, the latter being secured to the front end of the tube by screws 57 passing through said flange. The rod 47 extends through an opening in the disk 55 and through a notch in the flange 53. The disks 54 and 55 have flanges 58 which support a cylindrical screen 59 surrounding the forward portion of the Bunsen tube for filtering all of the air passing to the Bunsen tube through the openings 45.

Extending between the sides 3 adjacent the upper edges thereof and fastened at its ends to said sides is a support 60. This support has a downwardly and rearwardly inclined wall 61, the rear edge of which extends through a slot 62 in the upward extension 20 of the supporting plate 19. Carried by the support 60 is a fireclay header 63. There is a space 64 between the bar 11 and the upper edge of this header and said upper edge is covered by a sheet metal strip 65, shown in detail in Figure 12. Spaced lugs 11^a extend downwardly from the bar 11 into this space and engage the strip 65. It will be noted, by reference to Figures 8, 9, 10 and 11, that the header has a number of slots 66 in its upper rear edge portion intermediate lugs 67. The lugs 67 engage the metal back 2 and the slots 66 provide spaces through which the air flowing upwardly between the back 2 and the member 20 can pass. The member 65, it will be noted, is shaped to cover the upper edge of the header and has flanges 68 which engage the walls 69 of the slots. A packing 70 is interposed between the rear upper edge of the header and the upper end of the upward extension 20. This upward extension has an opening 71 therein surrounded by a suitable fitting 72 for connection to an off-take pipe.

Extending vertically between the sides 3 adjacent the rear edge of the slot 21 in the deck 19 is a corrugated sheet metal reflector 73, which is preferably calorized to resist oxidation at the high temperature to which it is subjected. The lower edge of the reflector is received in a channel member 73^a 125 secured to the upper face of the deck 19, while its upper edge engages in a groove 74 at the forward edge of the inclined wall 61 of the support 60.

The burner tips 33 and the lugs 38 project 130

upwardly through the slot 21 in the deck 19. Radians 75 have their lower ends seated upon the lugs 38 and have their upper ends positioned in an inverted trough 76 in the 5 header. The header overhangs the radians and acts as a top support for them and also as a hood to carry away the combustion products. In one end of the header there is an opening 77 which registers with a similar 10 opening (not shown) in the adjacent sheet metal side 3. A pyrophoric lighting device may be positioned adjacent these openings for lighting the heater. The handle 78 of such device is shown in Figure 1. The 15 trough 76 preferably has a partition 79 therein adjacent the opening 77. Interposed between the end radians and the sheet metal sides 3 are removable refractory end pieces 80 which protect the metal sides and prevent 20 them from burning out.

Having now described the invention in detail I will endeavor to point out the more important advantages thereof. The design 25 of the burner manifold and the Bunsen tube whereby the latter runs under the former and then curves up into the manifold permits of a properly constructed Bunsen tube without an excessive depth of hearth and brings the controls to the front of the heater. 30 The provision of the sliding sleeve 46 in connection with the primary air inlets 45 enables a rich mixture to be obtained at the top of the radians for ignition purposes. The clay header overhanging the radians 35 not only acts as a top support for them and as a hood to carry away the combustion products, but also provides an inverted trough throughout its length to trap some of the mixture, insuring ignition of all of the 40 radians at one time.

The air is permitted to flow upwardly through the space between the metal back 2 and the upward extension 20 and to pass out through the space 64 between the upper bar 45 11 and the upper edge of the clay header. This circulation of the air prevents the metal walls of the heater from becoming excessively hot, and provides means for effectively 50 circulating a heated air current through the space or room containing the heater, thereby increasing the effectiveness of the heater. Moreover, an air space is provided between the corrugated metal reflector 73 and the upward extension 20 which prevents the reflector 55 from becoming overheated.

The vitreous enamel hearth and side pieces give the effect of tile, and the front bar and hearth are easily removable for access to the gas connection without disturbing the rest 60 of the heater structure. The removable refractory end pieces between the end radians and the metal side walls prevent the latter from being burned out by reason of the heat radiated from the radians. The individual 65 multi-hole burner tips are easily removable

for cleaning or changing equipment and safe against flash back, and the air screen over the Bunsen air inlet filters out any dirt from the primary air, thereby preventing any clogging of the tips and distributing elements. These and other features of the invention result in a highly efficient heater. Furthermore, the heater is compact and of pleasing appearance.

While I have shown and described a preferred embodiment of my invention, it will be understood that changes may be made in the details of construction without departing from the spirit of the invention or scope of the appended claims.

I claim:

1. In a gas heater, a burner manifold extending longitudinally thereof and having spaced burner tips, a Bunsen tube extending from the front portion of the heater 85 transversely thereof and connected at its rear end to the manifold, said tube having inlets for gas and primary air at its forward end, and a valve operable from the front of the heater for controlling the air inlet to facilitate lighting, substantially as described.

2. In a gas heater, a burner manifold extending longitudinally thereof and having spaced burner tips, a Bunsen tube extending from the front portion of the heater transversely thereof and connected at its rear end to the manifold, said tube having inlets for gas and primary air at its forward end, and means operable from the front of the heater 95 for controlling both the gas supply and the air inlet, substantially as described.

3. In a gas heater, a burner manifold extending longitudinally thereof and having spaced burner tips, a Bunsen tube extending from the front portion of the heater transversely thereof and connected at its rear end to the manifold, said tube having inlets for gas and primary air at its forward end, a valve for controlling the primary air inlet, spring means normally maintaining said 105 valve open, and means operable from the front of the heater for closing said valve, substantially as described.

4. In a gas heater, a burner manifold extending longitudinally thereof and having spaced burner tips, a Bunsen tube extending from the front portion of the heater transversely thereof and connected at its rear end to the manifold, said tube having a plurality of peripheral air inlets in its forward 115 end portion and having an inlet for gas adjacent said primary air inlets, a sleeve slidably mounted on said forward end portion of the tube for controlling the primary air inlets, an air screen for the primary air surrounding said forward end portion of the tube, and means operable from the front of the heater for operating said sleeve and for controlling the gas supply, substantially as 120 described.

130

5. In a gas heater, a removable hearth, a burner manifold at the rear of said hearth extending longitudinally of the heater, burner tips projecting upwardly from said 5 manifold, a Bunsen tube extending transversely of the heater beneath said hearth and manifold and having its rear end portion curved upwardly and forwardly and attached to the manifold, said tube having a 10 gas connection and inlet for primary air at its forward end, and means operable from the front of said front bar for controlling the air inlet and the gas supply, substantially as described. 15 6. In a gas heater, a burner manifold extending longitudinally thereof and having spaced burner tips, radiants extending vertically above said tips, supporting means on said manifold engaging the lower ends of 20 said radiants and permitting access of secondary air to said radiants through said lower ends, and a header of refractory material extending longitudinally of the heater above said radiants, said header overhanging the upper end portions of said radiants 25 and acting as a top support and lighting means therefor, substantially as described. 7. In a gas heater, a burner manifold extending longitudinally thereof and having spaced burner tips, radiants extending vertically above said tips, supporting means engaging the lower ends of said radiants and permitting access of secondary air to said radiants through said lower ends, and a 30 header of refractory material extending longitudinally of the heater above said radiants, said header having an inverted trough extending longitudinally thereof and into which the upper end portions of said radiants project in supporting relationship, said trough constituting a lighting means for the heater, substantially as described. 35 8. In a gas heater, a back and sides extending forwardly therefrom, a horizontal 40 deck extending between said sides and having a longitudinally extending slot therein, a burner manifold extending longitudinally of the heater beneath said slot, burner tips projecting upwardly from said manifold, radiants supported on said manifold and extending vertically above said tips, a support 45 extending between said sides at the rear of the upper end portions of said radiants, and a metal reflector extending vertically between the sides at the rear of said radiants, said reflector having its lower edge in engagement with said deck and its upper edge in engagement with said support, substantially as described. 50 9. In a gas heater, a back and sides extending forwardly therefrom, a horizontal deck extending between said sides and having a longitudinally extending slot therein, a burner manifold extending longitudinally of the heater beneath said slot, burner tips projecting upwardly from said manifold, radiants extending vertically above said tips, a header of refractory material extending longitudinally of the heater above said radiants, said header 55 70 75 80 85 90 95 100 105 110 115 120 125 130

overhanging the upper end portions of said radiants and acting as a top support therefor, a metal partition extending upwardly from the rear edge of said deck plate and having its upper edge in engagement with the rear face of said header, and means extending through said partition and the back of the heater for carrying away the products of combustion, said partition and said back 10 providing a space therebetween for insuring an upward flow of cooling air through such space, substantially as described.

13. In a gas heater, a back and metal sides extending forwardly therefrom, a burner manifold extending longitudinally of the heater between said sides, spaced burner tips projecting upwardly from said manifold, radiants extending vertically above said tips, and removable end pieces of refractory 15 material arranged between the end radiants and the metal sides, substantially as described.

14. A gas heater, comprising side walls, radiants, and end pieces of refractory material between the end radiants and said side walls, said radiants and refractory end pieces being similarly removable, substantially as described.

15. In a gas heater, a burner manifold extending longitudinally thereof and having spaced burner tips, a Bunsen tube communicating substantially centrally of said manifold and extending transversely of the heater, said tube having inlets for gas and primary air adjacent the front of the heater, 30 and a valve operable from the front of the heater for controlling the primary air inlet, substantially as described.

16. In a gas heater, a heating means, a reflector cooperating therewith, means for supplying a combustible mixture to said heating means, and walls forming a dead air space adjacent said reflector and an air 35 circulating duct in spaced relation to said reflector, substantially as described.

17. In a heater, enclosing walls, heating means within said walls and in spaced relation thereto, a reflector adjacent said heating means, and an air circulation duct in spaced 40 relation to said reflector and adjacent the back wall of the heater, substantially as described.

In testimony whereof I have hereunto set my hand.

WILLIAM D. ANTRIM.

CERTIFICATE OF CORRECTION.

Patent No. 1,669,503.

Granted May 15, 1928, to

WILLIAM D. ANTRIM.

It is hereby certified that error appears in the printed specification of the above numbered patent requiring correction as follows: Page 3, line 122, claim 4, strike out the word "primary", and insert the same to follow after the word "peripheral" in line 120; page 4, line 93, claim 10, before the word "metal" insert the article "a"; and that the said Letters Patent should be read with these corrections therein that the same may conform to the record of the case in the Patent Office.

Signed and sealed this 19th day of June, A. D. 1928.

M. J. Moore,
Acting Commissioner of Patents.
